(57) **CLAIM**

The ornamental design of a fan blade, as shown and described.

DESCRIPTION

FIG. 1 is a perspective view of a fan blade;

FIG. 2 is a front elevation view thereof;

FIG. 3 is a top plan view thereof;

FIG. 4 is a bottom plan view thereof;

FIG. 5 is a rear elevation view thereof;

FIG. 6 is a left side elevation view thereof; and,

FIG. 7 is a right side elevation view thereof.

The broken line showing of environment structure in FIGS. 1-7 is for illustrative purposes only and forms no part of the claimed design.
